INVENTOR.

James M. Kenerson

United States Patent Office.

JAMES M. KENERSON, OF NEWPORT, NEW HAMPSHIRE, ASSIGNOR TO HIMSELF AND EDMUND BURKE, OF SAME PLACE.

Letters Patent No. 106,173, dated August 9, 1870.

IMPROVEMENT IN LAMP-SHADE AND REFLECTORS.

The Schedule referred to in these Letters Patent and making part of the same.

Be it known that I, JAMES M. KENERSON, of Newport, in the county of Sullivan and State of New Hampshire, have invented a new and useful Improvement in Lamp-Shades and Reflectors applied to the ordinary house-lamp, which I denominate "Kenerson's Improved Combined Lamp-Shade and Reflector;" and I do declare that the following is a full and exact description thereof, reference being had to the accompanying drawing, and to the letters of reference marked thereon, making a part of this specification.

The nature of my invention consists in the employment of highly burnished copper for the concave or reflecting-surface of lamp-shades and reflectors, which not only condenses and reflects the light of the lamp, but gives it a rich, mellow, golden hue, making it less dazzling and more agreeable to the eyes of persons using the lamp.

My improved shade and reflector consists of a concavo-convex plate, A, the inner or concave surface of which is made of highly polished or burnished copper, about four inches in diameter, the center of which may be made a little convex, if desired.

The outer or convex surface of plate A may be covered over with a slight coating of tin, or paint, of such color as may be preferred.

E is a slot soldered upon the convex surface of plate A, through which the angular spring C passes, and upon which the plate A can be made to move up and down, and adjusted at any desired point on the spring when in use.

B is a thumb-spring, constituted of the two side pieces b' and the spring D, the latter being made in the form of the letter V, by which the two side pieces b' are united, the spring B serving to fasten the shade and reflector to the neck of the lamp.

My improved shade and reflector may be used both as a shade and reflector. After having been fastened to the neck of the lamp by the thumb-spring B, if used as a shade, the convex surface of plate A should be turned toward the person using it, the plate A being adjusted at such a point on the angular spring C as convenience may require.

If it is desired to use plate A as a reflector, the concave surface should be placed on the opposite side of the lamp, turned toward the person using it, and adjusted at such a point upon the spring C as convenience may require.

When used as a reflector, the copper surface of plate A throws a rich and mellow light upon the object on which it is reflected. If reflected upon a printed page, it gives the paper that tinted color deemed so favorable to the eyes, and great distinctness to the printed letters.

The reflector may be made to surround the lamp wholly or in part, in which form, or in any form of a reflector, I claim the burnished copper surface, if used.

Having described the construction and uses of my improved lamp-shade and reflector,

What I claim, and desire to secure by Letters Patent, is—

The employment of polished or burnished copper surfaces in the construction of lamp-reflectors, as herein set forth.

JAMES M. KENERSON.
